STARTER JAW ACTUATING DEVICE

Samuel Gilbert, Cedar Grove, N. J., assignor to
Bendix Aviation Corporation, Teterboro, N. J.,
a corporation of Delaware

Application September 29, 1949; Serial No. 118,643

6 Claims. (Cl. 74—7)

1

The present invention relates to engine starters and particularly to engine starter meshing mechanism.

In engine starters usually some means are necessary for engaging the starter jaw with the engine to be started. One method used is to frictionally hold the starter jaws to cause axial movement thereof. This method has numerous disadvantages in that the friction means are present during the operation of the starter. Also for very cold starts, the friction means are not sufficient to cause the necessary axial movement of the starter jaws.

It is an object of the present invention to provide an improved meshing mechanism that will avoid the above difficulties.

Another object of the invention is to provide an improved starter having high axial torque on the starter jaws during the meshing period.

A further object of the invention is to provide an improved starter.

A further object is to provide an improved starter for operation at low temperatures.

The above and other objects and features of the invention will appear more fully hereinafter from a consideration of the following description taken in connection with the accompanying drawings wherein one embodiment of the invention is illustrated by way of example.

In the drawing:

Figure 1 is a sectional view of an engine starter embodying one form of the invention.

Figure 2 is a detailed view of one embodiment of the meshing mechanism.

Figure 3 is a detailed view of another embodiment of the meshing mechanism.

Referring to the drawing, the device therein shown comprises a starter assembly including, in general, a motor 1 having a driving shaft 2 rotatably supported by a bearing 3 mounted in end wall 4 of motor housing 5. A pinion 6, shown as integral with the shaft 2 meshes with planet gears 7. The planet gears 7 are rotatably supported by ball bearings 8 mounted on stub shafts 9 carried by spider cage 10. The planet gears 7 mesh with a ring gear 11 shown as integral with gear housing 12. The gear housing 12 is secured to the motor housing 5 by studs 13 and nuts 14 as shown or by other suitable means.

Integral with the spider cage 10 is a pinion gear 15 adapted to engage planet gears 16 which also engage the ring gear 11. The gears 16 are supported by bearings 17 mounted on stub shafts 18 carried by a drum member 19. The drum member or barrel 19 is rotatably mounted in the housing 12 by bearing 20.

2

The barrel 19 is connected for the transmission of rotary motion to axially stationary spline nut 21 through a torque limiting disc pack 22. The disc pack 22 comprises a plurality of friction discs alternately splined to the inner face of the barrel 19 and the outer face of the spline nut 21. The discs of the pack 22 are forced into frictional engagement with each other by a plurality of circumferentially spaced springs 23 compressed between a flange 24 on the spline nut 21 and an adjustable nut 25 threaded into the barrel 19 and set so that the disc pack 22 will slip at a predetermined torque.

The long lead internal threads of the spline nut 21 mesh with mating threads of screw shaft 26 which is connected to starter jaw 27 by axial splines 28 for rotation therewith.

The present invention provides novel means for actuating the starter jaw 27 into engagement with a crank shaft 29 or extension thereof of the engine to be started.

The pinion gear 15 has a shaft 30 extending axially therefrom into the barrel 19 and journaled by bearings 31 and 32 engaging enlarged sections 33 and 34 respectively of shaft 30. The bearings 31 and 32 are supported by an axially projecting inner drum member 35 of the barrel 19. The shaft 30 terminates in an externally helically grooved screw section 36. The pitch of the threads of the screw section is less than that of the screw shaft 26 and spline nut 21.

The clutch jaw 27 is retained in operative engagement by a mesh rod 37 secured to the clutch jaw 27 by a nut 27a. The mesh rod 37 extends into the screw shaft 26 and terminates in a flange 38 and has a counterbore 39 concentric with the shaft 30. A plurality of balls 40 adapted to mesh with the threaded portion 36 are mounted in the flange 38 by means of holes 41, whose centers are spaced to form an angle equal to the pitch angle of the threaded section 36. The balls are retained in the holes 41 by peening the holes 41 or in any other suitable manner. Springs 42 urge the balls into engagement with the threaded portion 36. The springs 42 are held in place by screw caps 43 inserted in the holes 41. A spring 44 coacts between the flange 38 of the mesh rod 37 and a spring retaining ring 45. The retaining ring 45 is held in the screw shaft 26 by a split ring 46 fitted in a groove 47 in the shaft 26.

An oil seal 48 surrounds the outer circumference of the clutch jaw 27 and is held in position by a bracket 49 clamped between a flange 50 on the gear housing 12 and the engine crank case 51 by means of studs 52 and nuts 53 or any other suitable manner.

In operation, when the motor 1 is energized rotary motion is imparted to the barrel by means of the planetary gear system which includes the pinion 15. The shaft 30 being integral with the pinion 15 rotates therewith. The helical threaded portion 36 coacts with the balls 40 providing a screw like action that causes the mesh rod 37 to move axially to actuate the starter jaw 27 and screw shaft 26 into operative position. Inasmuch as the speed of rotation of the shaft 30 is greater than that of the barrel 19, the jaw 27 is moved axially to its engaging position with a relatively small amount of rotation of the barrel 19. The flange 38 of the mesh rod 37 coacts with a flange on the screw shaft 26 so that as the mesh rod 37 is moved axially toward the engine engaging position, the screw shaft 26 is also moved axially. The pitch of the long lead splines between the spline nut 21 and the screw shaft 26 is such that the force exerted by the meshing rod in the axial direction moves the screw shaft 26 axially relative to the nut 21. Upon the starter jaw 27 reaching operative position, the balls 40 will have passed the end of the shaft 30 and are out of mesh with the threaded portion 36 thereby allowing free rotation while cranking the engine. Should the jaws abut before meshing the springs 42 will yield and permit the balls 40 to ratchet over the threads 36. Also any undue resistance to axial movement of the starter jaw 27 will cause the balls 40 to ratchet over the threads 36. When the jaw 27 is in the retracted position, as shown, the balls 40 prevent the jaw 27 from being moved into engagement by vibration.

Referring now to Figure 3 for a modification of the structure illustrated in Figure 1, wherein a cylindrical mesh rod 50 is secured to the starter jaw 27 by a nut 27a. The rod 50 has a shoulder portion 51 adapted to cooperate with the spring 44 to urge the jaw 27 into engagement with the engine jaw 29. The end of the mesh rod 50 away from the jaw 27 has a counterbore 52 concentric with the shaft 30. The counterbore 52 has a threaded portion 53 adapted to mate with the threaded portion 36. The remaining part of the counterbore 52 is relieved for clearance for the threaded portion 36. In order to provide flexibility of the threaded portion 53 the mesh rod 50 which is spring steel has a plurality of longitudinal slots 54 extending the length of the counterbore 52.

In this embodiment, the shoulder 34 and bearing 32 are omitted, the threaded portion 36 of the shaft 30 being formed adjacent to the shoulder 33. The operation is similar to that described for Figure 1. The threaded portion 36 coacts with the mating threads 53 in the mesh rod 50 and drives the jaw 27 into engagement. The longitudinal slots permit the threads 53 to ratchet over the threads 36 should the jaw abut before engagement. In the engaged position, the threads 53 are beyond the threads 36 thus permitting free rotation of the starter jaw 27.

Inasmuch as the speed of rotation of the shaft 30 is greater than that of the barrel 19, the jaw 27 is moved axially to its engaging position with a relatively small amount of rotation of the barrel.

Thus the disadvantages of a friction ring normally used to provide axial movement of the starter jaw are overcome and a positive drive provided which insures meshing, even on cold starts and also retains the jaw in its retracted position when the engine is running.

Although only two embodiments of the inven-

tion have been illustrated and described, various changes in the form and relative arrangement of the parts, which will now appear to those skilled in the art, may be made without departing from the scope of the invention.

What is claimed is:

1. In an engine starter, the combination of an assembly comprising an axially stationary rotatable spline nut, a screw shaft in said nut, a starter jaw member adapted for rotation with and axial movement relative to said screw shaft, means including a positive driven helical screw for actuating said starter jaw axially to an engine engaging position, yieldable means for drivably connecting said helical screw to said starter jaw, said last means being adapted to yield and release said connection when the opposition to axial movement of said starter jaw exceeds a predetermined maximum.
2. For use in an engine starter, the combination of an assembly comprising an axially stationary rotatable spline nut, a screw shaft connected for rotation with and axial movement relative to said spline nut, a starter jaw adapted for rotation with and axial movement relative to said screw shaft, a jaw retaining member extending into and having a shoulder adapted to engage said screw shaft, means including an externally threaded shaft for coacting with said jaw retaining member for driving said member axially to an engine engaging position, said jaw retaining member having ball receiving openings at spaced intervals along a helical path corresponding in pitch to the pitch of said externally threaded shaft, balls positioned in said openings and spring means for resiliently biasing said balls into engagement with said externally threaded shaft.
3. For use in an engine starter, the combination of an assembly comprising an axially stationary rotatable spline nut, a screw shaft connected for rotation with and axial movement relative to said spline nut, a starter jaw adapted for rotation with and axial movement relative to said screw shaft, a jaw retaining member extending into and having a shoulder adapted to engage said screw shaft, means including an externally threaded shaft for coacting with said jaw retaining member for driving said member axially to an engine engaging position, said jaw retaining member having a yieldable internally threaded portion adapted to engage said externally threaded shaft and to ratchet over said externally threaded shaft upon abutment of said starter jaw.
4. In an engine starter, the combination of an assembly comprising rotatable driving means, an axially stationary rotatable spline nut, a planet gear assembly for connecting said spline nut to said driving means, a screw shaft interposed in said splined nut and having mating splines thereon, a starter jaw member splined to said screw shaft for rotation with and axial movement relative to said screw shaft, a jaw retaining member having a circumferential flange extending into said screw shaft, means including a helically threaded member rotatably connected to said driving means, helical means secured to said flange and adapted to coact with said threaded member to translate rotary motion to lateral motion to move said starter jaw axially to an engine engaging position, said last means being yieldable to permit ratcheting of said threaded member to interrupt said axial movement upon abutment of said starter jaw.

5. For use in an engine starter, a starter jaw actuating mechanism comprising, in combination, a starter jaw to be actuated, a jaw retaining member securely attached to said starter jaw at one end thereof, said jaw retaining member having a counterbore at the other end, a shaft member concentric with said counterbore, said shaft member and said counterbore having mating parts adapted to coact to form a jack screw for actuating said starter jaw axially to an engine starting position, one of said coacting parts being yieldable to permit ratcheting when said starter jaw reaches said engine starting position.

6. In an engine starter having a starter jaw adapted to move axially to engine engaging position upon energization of said starter, the combination comprising an axially stationary rotatable spline nut, a screw shaft connected for rotation with and axial movement relative to said spline nut, a starter jaw adapted for rotation with and axial movement relative to said screw shaft, a jaw retaining member securely attached to said starter jaw and having a counterbored portion extending into said screw shaft, spring

means for yieldably biasing said screw shaft and said jaw retaining member against relative axial movement, a shaft having a helical externally threaded portion concentric with said counterbored portion, said counterbored section having an internal threaded portion adapted to mesh with said externally threaded portion to move said jaw retaining member axially upon rotation of said shaft, said jaw retaining member cooperating with said screw shaft to move said starter jaw to an engine engaging position, and means including a plurality of axial slits in said counterbored portion to permit ratcheting of said threaded portions when opposition to said axial movement exceeds a predetermined value.
